GOLF CLUB HEAD

Robert S. Bartron, Liss, England, assignor to Robert R. Shaefer, Arlington, Va.

Filed Dec. 10, 1971, Ser. No. 206,984

Term of patent 14 years

Int. Cl. D21—01
U.S. Cl. D34—5 GH

FIG. 2

FIG. 1

FIG. 3

FIG. 4

FIG. 5

FIG. 1 is a perspective view as seen from above and the front of the golf club head embodying my new design;

FIG. 2 is a side view thereof;

FIG. 3 is an end view thereof;

FIG. 4 is a plan view from below thereof; and

FIG. 5 is a cross-sectional view on the line 5—5 of FIG. 4.

I claim:

The ornamental design for a golf club head, as shown.
